WORM SIMULATING TOY

Clifford F. Dawson, Wallingford, Vt.

Application June 16, 1950, Serial No. 168,538

2 Claims. (Cl. 46—104)

1

This invention relates to a mechanical toy, and more particularly to such a toy which is adapted to crawl across the surface and simulate the motions of a worm or the like.

An object of this invention is to provide a mechanical toy which is particularly adapted to crawl over a surface with its central section alternately rising into a humped position and dropping into a straight position intermediate the head and tail sections of the toy.

Another object of this invention is to provide a mechanical toy in which the head and tail sections alternately approach and recede from each other.

A further object of this invention is to provide a mechanical toy in which the head section is movable forwardly to effect the receding movement with respect to the tail section, and the central section is moved into a humped position to effect the approaching movement of the head and tail sections with respect to each other.

A still further object of this invention is to provide a worm-simulating mechanical toy which is simple in construction and relatively cheap to manufacture.

The above and still further objects and advantages of the invention will become apparent upon consideration of the following detailed description of the invention, when taken in conjunction with the accompanying drawings, wherein:

Figure 1 is a side elevational view, with parts broken away and in section, of the worm-simulating toy of the present invention, shown in its humped position;

Figure 2 is a sectional elevational view of the head section of the worm-simulating toy of the present invention, showing the operating mechanisms for effecting a movement of the toy; and

Figure 3 is a sectional view taken along the line 3—3 of Figure 2.

Referring now more particularly to the drawings, wherein like reference numerals have been used throughout the several views to designate like parts, there is shown the worm-simulating toy of the present invention, generally designated by the numeral 10, which comprises a hollow body 11 including a head section 12, a tail section 13 disposed in end-to-end spaced relation with respect to the head section 12, and a central connecting section 14 fabricated of any suitable flexible material disposed intermediate the head and tail sections and secured therebetween.

Disposed transversely of the head section 12 is a drive shaft 15 which has one end journaled in

2

one side wall of the head section, as indicated by the reference numeral 16, Figure 3, and has its other end operatively connected to the drive element of a spring motor 17 which is disposed interiorly of the head section 12 and supported on a side wall thereof. The spring motor 17 is wound by means of a key 18 which is disposed exteriorly of the head section 12 contiguous to the wall supporting the spring motor and is operatively connected to the spring motor by means of a connecting shaft 19.

The bottom wall of the head section 12 is provided with two spaced apart, transversely extending slots, generally designated by the reference numerals 20, 21. Disposed transversely of the head section 12 and overlying the slot 20 is a front axle 22 which has its ends rotatably journaled in the opposed side walls of the head section, as clearly indicated by the reference numerals 23, 24, Figure 3. Carried by the front axle 22 in spaced opposed relation with respect to each other are the front wheels 25, 26 which have their peripheries extending through the slot 20 for engagement with a ground surface.

Overlying the slot 21 is a transversely disposed rear axle 27, the axle being rotatably journaled in the side walls of the head section 12 and carrying the rear wheels, generally designated by the reference numeral 28. Accordingly, the head section 12 is mobile and can traverse a ground surface.

Disposed longitudinally of the head section 12 above the drive shaft 15 is a rod 29 which is mounted intermediate its ends for reciprocatory movement longitudinally of the head section 12 by means of the spaced apart guides 30, 31. One end of the rod 29 extends into the flexible central section 14 and is movable toward and away from the latter upon reciprocation of the rod 29. Circumposed about the other end of the rod 29 is a spring 32 which normally urges the rod 29 into a position wherein the rod 29 is biased away from the flexible central section 14.

Disposed within the flexible section 14 is a plate 33 which is carried by the head section 12. Disposed longitudinally by the flexible section 14 is an L-shaped lever, generally designated by the reference numeral 34, which is supported intermediate its long leg 35 and its short leg 36 on the plate 33 for rocking movement about a transverse axis provided by the pivot pin 37 from a horizontal position to a vertical position. As clearly shown in Figure 2, the adjacent end of the rod 29 bears against the short leg 36 of the lever 34 and urges the lever to the dotted line

position shown in Figure 2 upon movement of the rod 29 toward the flexible section 14. When the lever 34 assumes the vertical position, as clearly shown in Figure 1, the flexible central section 14 will be urged into its humped position. It is to be noted that the lever 34 is counterbalanced so that it will normally assume the horizontal position when the rod 29 is brought out of engagement with the short leg 36 thereof.

Disposed within the tail section 13 is a weight, generally designated by the reference numeral 38, the weight providing the desired drag to the tail section and cooperating with the central and head sections to effect the desired movement of the toy.

Carried by the drive shaft 15 is a coupling means, generally designated by the reference numeral 40, which is alternately engageable with the rotary axis of the front wheels 25, 26, and the rod 29 for periodically effecting the rotary movement of the former and the movement of the latter toward and away from the flexible central section 14. The coupling means 40 embodies a sector gear 41 arranged axially on the drive shaft 15 and secured thereto. A portion of the outer periphery of the sector gear 41 is provided with gear teeth 42 for engagement with a pinion gear 43 carried by the front axle 22. Accordingly, during a portion of the rotary cycle of the sector gear 41, the teeth 42 will mesh with the teeth of the pinion 43 to thereby effect the movement of the front wheels 25, 26, and to cause the head section to move forwardly along the supporting surface. The coupling means 40 further embodies an eccentric pin 44 disposed transversely of the sector gear 41 and secured thereto. The pin 44 is selectively engageable with a fixed lug 45 depending from the rod 29. The spacing of the pin 44 is selected with respect to the gear teeth 42, so that the pin 44 and lug 45 are engageable with each other during the portion of the rotary cycle of the sector gear in which the teeth 42 are not in meshing engagement with the pinion 43. As clearly shown in Figure 2, counterclockwise movement of the sector gear 41 during the period in which the pin 44 bears against the lug 45 will urge the rod 29 toward the flexible central section 14 into engagement with the lever 34 to thereby cause the flexible section 14 to assume its humped position. Accordingly, the toy will crawl over the supporting surface with its central section alternately rising into a humped position and dropping into a straight position intermediate the head and tail sections.

In actual use, the spring motor 17 is manually wound by means of the key 18 and the toy 10 is supported on a surface to be traversed. Upon release, the control wheel 41 will alternately actuate the lever 34 and the front wheels 25, 26 to thereby cause the toy to crawl across the surface and to simulate the motions of a worm.

Although only one embodiment of the mechanical worm-simulating toy of the present invention has been described, numerous modifications can be made without departing from the spirit of the invention as set forth in the appended claims.

What I claim is:

1. In a toy, an elongated hollow body including a head section, a tail section spaced axially from said head section, and a center section positioned

between and connected at its ends to the adjacent ends of the head and tail sections, said center section being flexible relative to said head and tail sections, an endwise slidable rod mounted longitudinally in said head section, spring means normally biasing said rod forwardly in said head section to an inoperative position, a lever pivotally mounted on the rear of said head section having a first arm extending in said center section, said first arm being weighted to normally occupy a reclining position extending longitudinally of the head section, said lever having a second arm projecting laterally with respect to said first arm and normally occupying a transverse position relative to said head section and in the region of the rearward end of said endwise slidable rod, and motor means in said head section including a rotary member having a portion periodically engaged with a portion on said rod for pushing said rod rearwardly against the resistance of said spring means so as to engage said rod against said second lever arm and swing said first lever arm to a position transverse to said head section and thereby flex said center section out of alignment with said head and tail sections.

2. In a toy, an elongated hollow body including a head section, a tail section spaced axially from said head section, and a center section positioned between and connected at its ends to the adjacent ends of the head and tail sections, said center section being flexible relative to said head and tail sections, an endwise slidable rod mounted longitudinally in said head section, spring means normally biasing said rod forwardly in said head section to an inoperative position, a lever pivotally mounted on the rear of said head section having a first arm extending in said center section, said first arm being weighted to normally occupy a reclining position extending longitudinally of the head section, said lever having a second arm projecting laterally with respect to said first arm and normally occupying a transverse position relative to said head section and in the region of the rearward end of said endwise slidable rod, and motor means in said head section including a rotary member having a portion periodically engaged with a portion on said rod for pushing said rod rearwardly against the resistance of said spring means so as to engage said rod against said second lever arm and swing said first lever arm to a position transverse to said head section and thereby flex said center section out of alignment with said head and tail sections, said head section having ground engaging wheel means thereon, and means operatively connecting said rotary member to said wheel means whereby said wheel means is operated only while said endwise slidable rod is idle in inoperative position.
